LIQUID DISPENSING DEVICE

David H. Hawes, Bridgeport, Conn.

Application September 29, 1934, Serial No. 746,062

10 Claims. (Cl. 221—102)

This invention relates to new and useful improvements in brushes and has particular relation to an automatic shaving brush.

An object of the invention is to provide a brush including means for feeding a measured charge of liquid soap or the like into the bristles of the brush.

Another object is to provide a brush including means whereby on a simple manipulation a measured charge of liquid soap or the like is forced into the brush bristles.

A further object is to provide a brush having the characteristics stated, which is of relatively simple construction and is easily operated, and which may be easily cleaned by placing it under a faucet in the usual manner.

Other objects and advantages will become apparent from a consideration of the following detailed description taken in connection with the accompanying drawing wherein a satisfactory embodiment of the invention is shown. However, it will be understood that the invention is not limited to the details disclosed but includes all such variations and modifications as fall within the spirit of the invention and the scope of the appended claims.

In the drawing:

Fig. 1 is a view partly in elevation and partly in section showing the improved brush with the handle thereof empty of liquid soap and with the soap measuring and projecting parts in normal position, communication between the interior of the handle and the bristles of the brush being cut off;

Fig. 2 is an enlarged sectional view through the juncture of the bristles and handle, parts being broken away, and showing the measuring and projecting parts in their normal positions;

Fig. 3 is a view similar to Fig. 2 but showing the locations of the parts at the beginning of the operation of projecting the soap into the brush bristles;

Fig. 4 is a sectional view taken substantially along the line 4—4 of Fig. 2;

Fig. 5 is a sectional view taken substantially along the line 5—5 of Fig. 3;

Fig. 6 is a view showing partly in elevation and partly in section the various parts of the mechanism in the order of their assembly;

Fig. 7 is a bottom plan view with a part broken away showing a body member employed;

Fig. 8 is a vertical sectional view through a control member employed;

Fig. 9 is a top plan view of the member of Fig. 8 with parts broken away;

Fig. 10 is a side elevational view of a stop sleeve;

Fig. 11 is a side elevational view with parts broken away showing the control member;

Fig. 12 is a top plan view of a plunger;

Fig. 13 is a side elevational view of said plunger. 5

Referring in detail to the drawing, at 15 is generally indicated the hollow handle of the brush which handle comprises a container for a liquid, as soap, and at its open end is provided with a neck portion 16 removably connected to an 10 operating member 17 located against one side of a body 18 at the other side of which is located the brush head 19. The body 18 includes an upwardly extending annular flange 20 and a downwardly extending annular flange 21 internally 15 screw threaded as at 22. Further, this body includes a downwardly projecting tubular extension 23 including a bottom wall 24 perforated as at 25. The extension 23 is concentric with the annular flange 21, and in alignment with said extension 20 20 23 is an upwardly projecting extension 26 provided in its opposite sides with longitudinally extending slots 27 extending through the outer end thereof and terminating slightly above the upper surface of the inner or bottom wall 28 of the 25 operating member 17

Brush head 19 includes the bristles 29, the inner or butt ends of which are set in rubber as at 30, and which butt ends are received between metal rings 31 and 32 of which the latter is externally 30 screw threaded for engagement with the threads 22 in the inner periphery of the depending body flange 21. The inner ring 31 of the brush head is of a diameter to rather snugly receive the inner extension 23 of the body member 18 as clearly 35 shown in Figs. 1, 2 and 3, and when the brush head is threaded to the body member 18 the extension 23 of said member enters or projects into the brush head through the ring 31 thereof.

The operating member 17 includes an annular 40 wall 33 on its inner side screw threaded as at 34 for the reception of the externally screw threaded neck 16 of the handle and reservoir 15. The outer surface of the wall 33 is smooth and bears against the inner surface of the outwardly or upwardly projecting annular flange 20 of the body 18 so that it will be understood that the operating member is turnable on the body. Member 17 has an opening 35 therethrough and through which projects the upper or outer tubular extension 26 of the body, and extending upwardly at opposite sides of said opening are a pair of cam portions 36 each having an inclined edge 37 extending from its lower end to a top flat surface 38 between the inclined surface 37 and the 55

straight vertical edge 39. As shown best at 40 in Figs. 8 and 11 the lower ends or the starts of the inclined edges 37 of the cam portion 36 are flush with the upper or outer surface of the bottom wall 28 of the member 17 whereby such portions of the cam surfaces are slightly below the inner ends of the slots 27 of the body extension 26.

Cam portions 36 are transversely curved or are parts of cylindrical tube so as to bear against the outer surfaces of the body extension 26, and it will be noted that said portions extend upwardly a substantial distance at the outer side of said extension. A plunger 41 operates in the body extensions 23 and 26, and this plunger while open at its upper end is provided with a bottom wall 42, and adjacent its upper end carries laterally extending lugs 43 which lugs are received in and project through the slots 27 in opposite sides of the body extension 26 when the plunger is mounted on the body. Against the bottom wall 24 of the lower body extension 23 there is arranged a rubber or other ring 44 and when the plunger 41 is in normal position it is seated against this ring forming therewith a seal and preventing the movement of liquid from the hollow handle 15 into the head of the brush.

Inwardly of its outer end the upper body extension 26 is provided with lateral slots 45 each opening into one of the longitudinal slots 27 of said extension and each notched in its upper side at its inner end as at 46 (see Fig. 6). When the plunger 41 is dropped into place a coil spring 47 is inserted into the extension 26 and the lower or inner end of this spring enters the hollow plunger as in Figs. 1, 2 and 6. The upper end of said spring 47 bears against a cap 48 including on its underside an annular flange 49 providing a pocket-like portion 50 for the reception of said upper portion of the spring.

40 Lugs 51 extend from opposite sides of the flange 49 and when applying the cap 48 the same is manipulated to have its pocket 50 receive the upper end of the spring 47 and to bring its lugs 51 into alignment with the longitudinal slots 27 of the body extension 26. Thereafter, the cap is forced downwardly to bring its lugs 51 opposite the entrances to the lateral slots 45 and the cap is given a slight turn to carry its lugs to the inner ends of said slots. Thereafter, on the cap being 45 released, the spring in attempting to force the cap outwardly will shift the cap to dispose its lugs 51 in the notches 46 in the upper edges of the slots 45 so that the cap is held against casual turning movement.

55 On its outer surface each cam portion 36 is provided with a lug 52 and before the cap 48 is assembled on the device as above explained but after the plunger 41 is in the body a stop sleeve 53 is applied. This sleeve is provided with 60 notches 54 opening through its lower end and the sleeve is mounted by passing it over the body extension 26 and positioning it with the lugs 52 of the cam portions in the notches or recesses 54 of the sleeve. With this construction the sleeve 65 53 will turn with the operating member 17, and on the inner surface of the sleeve are a pair of longitudinal lugs or ribs 55 so located with respect to one another and to the notches 54 that when the sleeve is on the cam portions 36 of the 70 operating member each lug 53 has one of its vertical edges located opposite and in such spaced relation to a vertical edge 39 of a cam portion 36 as to leave a vertical passageway equal to the width of a laterally projecting lug 43 of the 75 plunger 41. Owing to the length of the lugs 55

the mentioned vertical edge of each lug projects above and below the flat or free end 38 of that cam portion 36 with which it is associated.

In assembling the brush the head 19 may be threaded to the flange 21 of the body 18 and then the operating member 17 may be applied to the other side of the body. Thereafter the plunger 41 is dropped into place with its lugs 43 extending through the longitudinal slots 27 in the outer or upper body extension 26. With the plunger in position the stop sleeve 53 may be applied by positioning it on the operating member with the lugs 52 of the cam portion of the latter in the recesses 54 in the lower edge of the sleeve. The coil spring 47 may now be applied by inserting 15 the inner end thereof into the plunger and the cap 48 may then be positioned as above described and to secure the coil spring. If desired, a suitable spring means as, for example, the spring washer 56 may be interposed between the 20 flange of the cap 48 and the upper end of the stop sleeve 53 and this spring washer will act to hold such sleeve in position and will also act to exert an outward pressure on the cap 48 to maintain the lugs 51 thereof in the recesses 46 of the 25 slots 45.

With the parts assembled as described the lower end of the plunger 41 will be against the ring 44 and form therewith a seal and the plunger will be held in this position by the coil spring 30 47. The hollow handle or reservoir 15 substantially filled with liquid shaving soap may then be secured to the operating member 17 as by threading the neck 16 of said handle into the operating member with the cam portions 36 and the body extension 26 and parts carried thereby located within the handle. The plunger lugs 43 are normally, that is, when the plunger is in normal position, located at the inner ends of the longitudinal slots 27 of the body extension 26 and 35 in the path of cam surfaces 37.

If it is now desired to use the brush the body 18 thereof and the operating member 17 are given a relative turning movement with the device held in an upright position with the bristles or head 19 down as shown in Fig. 1. This may be accomplished by holding the brush head as by gripping knurled surfaces 20a of the body 18 and turning the handle 15 or vice versa, or by gripping the body and the operating member by 45 knurled surfaces 17a and turning one of them relative to the other or turning them in opposite directions. It will be understood that the handle 15 being screw threaded to the operating member 17 these two parts will turn together, and that 50 the brush head 19 being screw threaded to the body 18 such two parts will turn together.

When a relative turning movement between the body 18 and the operating member 17 takes place the inclined cam surfaces 37 passing beneath and acting against the lugs 43 of the plunger act to retract the plunger or lift it upwardly away from its seat on the ring 44 and into a position in the upper or outer body extension 26 above the lower ends of the slots 27 thereof as in 60 Fig. 3. With the slots thus opened liquid from the handle enters the body extensions 23 and 26 so that the former becomes filled. As the turning movement continues the inclined cam surfaces 37 move from under the lugs 43 of the 65 plunger and while the flat surfaces 38 of the cam portions move under such lugs the plunger is maintained retracted against the action of the coil spring 47 so that there is a short time interval during which the plunger remains stationary. 70 75

This is to insure the filling of the lower body extension 23 before the release of the plunger.

As the flats 38 of the cam portions 36 move from beneath the plunger lugs 43 the spring 47 forces the plunger to normal position causing the plunger to project the predetermined or measured charge of liquid from the body extension 23 into the brush head through the openings or perforations 25 in the bottom wall 24 of said extension. It will be appreciated that during its return movement the plunger as its lower end passes the inner ends of the slots 27 closes off said slots preventing the escape of the liquid from the body extension 23 into the handle so that said liquid must pass outwardly through the perforations 25 into the brush head. The lugs 55 of the stop sleeve 53 act as stops or limiting means so that if the relative turning movement referred to is rapid the plunger lugs 43 cannot be carried over to a position above the inclined cam surfaces 37 which would act to prevent the plunger reaching normal position. If the movement is rapid then the plunger lugs 43 will simply engage the lugs 55 of the sleeve 53 and further relative turning movement of the parts is prevented until after the plunger has been returned to normal position to carry the plunger lugs 43 below the lower ends of the lugs or ribs 55.

From the foregoing description it will be clear that on each one-half relative rotation of the operating member 17 and the body 18 a measured charge of liquid will be forced into the brush head 19. It should be understood that the soap or other material in the handle 15 should be of proper consistency to flow into the cylinders 26 and 23 after the plunger is raised and then forced through the openings 25 by the plunger. A liquid soap has been found satisfactory. According to the present plan when the handle 15 has been emptied it will be discarded and another receptacle of liquid will be threaded to the operating member in place thereof. These refill reservoirs may be furnished closed with a cap, and when one becomes empty it may be removed from the brush 45 and the brush with the associated feed device attached to the new and filled reservoir making the device again ready for use. The brush may be cleaned by washing under a faucet in the usual manner.

Having thus set forth the nature of my invention, what I claim is:

1. In a device of the character described, a body having a discharge opening, an operating member turnable on said body, a liquid container, and means mounted on said body and extending into said container and operable by said operating member on relative turning movement of said body and operating member to force liquid from said container through said discharge opening.

2. In a device of the character described, a body having a discharge opening, an operating member at one side of the body and turnable thereon, a liquid container, and means mounted on said body and extending through and operable by said operating member to force liquid from the container through the discharge opening on relative turning movement of the operating member and body.

3. In a device of the character described, a body having a discharge opening, an operating member at one side of the body and turnable thereon, a liquid container, and means mounted on said body and extending through and operable by said operating member to force a measured

charge of liquid from the container through said opening on relative turning movement of the operating member and body.

4. In a device of the character described, a body having a discharge opening, an operating member at one side of said body and turnable thereon, a liquid container having an open end secured to said operating member, a passage from said container to said discharge opening, a plunger normally closing said passage, cam means to move said plunger from normal position on relative turning of the body and operating member to admit liquid from the container into said passage, and spring means to return said plunger to normal position and have it force the liquid from the passage through the opening.

5. In a device of the character described, a body having a discharge opening, an operating member at one side of said body and turnable thereon, a liquid container having an open end secured to said operating member, a passage from said container to said discharge opening, a plunger normally closing said passage, cam means to retract said plunger a predetermined distance from normal position and then release it on relative turning of the operating member and body to admit a predetermined quantity of liquid from the container into the passage, and spring means operable on release of the plunger by the cam means to return the plunger to normal position and have it force the predetermined quantity of liquid from the passage through the opening.

6. In a device of the character described, a body having a discharge opening, an operating member at one side of said body and turnable thereon, a liquid container having an open end secured to said operating member, a passage from said container to said opening, a plunger, a spring normally maintaining said plunger in position in and closing said passage, and cam means on said operating member and operable to retract said plunger a predetermined distance against the action of said spring and then release the plunger, whereby to admit a predetermined quantity of liquid into the passage from the container and then have said liquid forced from the passage through the opening by the plunger as it is returned to normal position by the spring.

7. In a device of the character described, a body having a discharge opening, an operating member at one side of said body and turnable thereon, a liquid container having an open end secured to said operating member, a tubular member extending into the container and providing a passage from the container to the body, said tubular member having an opening in its side within the container and having its end within the body partially closed, a sealing ring within the body end of said tubular member, a plunger in said tubular member, a spring normally maintaining said plunger in position on said sealing ring closing said passage, and cam means on said operating member and operable to retract said plunger a predetermined distance to expose the opening in the side of the tubular member to admit liquid into the latter from the container and then release the plunger, whereby to admit a predetermined quantity of liquid into the tubular member from the container and then have said liquid forced from the tubular member through the discharge opening by the plunger as it is returned to normal position by the spring.

8. In a device adapted to be used in a fountain

- brush for feeding soap, a hollow handle comprising a reservoir, a body member having a discharge opening and a tubular extension communicating with said reservoir, an operating member at one side of said body and rotatable about said tubular extension, said extension having slots in its opposite walls, a plunger in said extension and having oppositely extending lugs projecting through said slots, a spring normally maintaining said plunger in an inner position closing communication between the interior of the handle and the discharge opening, and said operating member including cam portions at the sides of said extension and each including an inclined cam surface and a straight vertical edge whereby on relative rotation of the operating and body members the plunger is drawn into said extension by engagement of the cam surfaces with the lateral lugs of the plunger to permit liquid from the handle to enter the extension and is released on the lugs and cam surfaces passing whereby to have the spring operate the plunger to force the liquid from the said extension through the discharge opening.
9. In a device adapted to be used in a fountain brush for feeding soap, a hollow handle comprising a reservoir, a body member having a discharge opening and a tubular extension communicating with said reservoir, an operating member at one side of said body, and rotatable about said tubular extension, said extension having slots in its opposite walls, a plunger in said extension and having oppositely extending lugs projecting through said slots, a spring normally maintaining said plunger in an inner position closing communication between the interior of the handle and the discharge opening, said operating member including cam portions at the sides of said extension and each including an inclined cam surface and a straight vertical edge whereby on relative rotation of the operating and body members the plunger is drawn into said extension by engagement of the cam surfaces
- with the lateral lugs of the plunger to permit liquid from the handle to enter the extension and is released on the lugs and cam surfaces passing whereby to have the spring operate the plunger to force the liquid from the extension through the discharge opening, a stop sleeve on and extending above said cam portions, and lugs on the inner side of said sleeve and spaced from the vertical edges of the cam portions a distance equal to the widths of the plunger lugs to limit relative turning movement of the plunger and operating member on the lugs passing off the cam portions of the latter.
10. In a device adapted to be used in a fountain brush for feeding soap, a hollow handle comprising a reservoir, a body member having a discharge opening and a tubular extension communicating with said reservoir, an operating member rotatable about said tubular extension, said extension having slots in its opposite walls, a plunger in said extension and having oppositely extending lugs projecting through said slots, a coil spring in said tubular extension and bearing at one end against the plunger and normally maintaining said plunger in an inner position closing communication between the interior of the handle and the discharge opening, a removable cap on the outer end of said tubular extension and against which the other end of said spring bears, and said operating member including cam portions at the side of said extension and each including an inclined cam surface and a straight vertical edge whereby on relative rotation of the operating and body members the plunger is drawn into said extension by engagement of the cam surfaces with the lateral lugs of the plunger to permit liquid from the handle to enter the extension and is released on the lugs and cam surfaces passing whereby to have the spring operate the plunger to force the liquid from the extension through the discharge opening.

DAVID H. HAWES.
